A. B. BURRESE,
GAS TANK SAFETY LOCK,
APPLICATION FILED MAR. 25, 1920.

1,372,400.

Patented Mar. 22, 1921.

Inventor
A. B. Burrese.

By *Alfredo Randolph Jr.*

Attorney.

UNITED STATES PATENT OFFICE.

ALBERT B. BURRESE, OF SEDRO WOOLLEY, WASHINGTON.

GAS-TANK SAFETY-LOCK.

1,372,400.

Specification of Letters Patent. Patented Mar. 22, 1921.

Application filed March 25, 1920. Serial No. 368,810.

To all whom it may concern:

Be it known that I, ALBERT B. BURRESE, a citizen of the United States, residing at Sedro Woolley, in the county of Skagit 5 and State of Washington, have invented certain new and useful Improvements in Gas-Tank Safety-Locks; and I do hereby declare the following to be a full, clear, and exact description of the invention, such as 10 will enable others skilled in the art to which it appertains to make and use the same.

This invention relates to new and useful improvements in tank safety locks and has for its primary object the provision of 15 means which will effectively close both the filling and outlet ports of a tank against being opened by an unauthorized person, thereby providing a device especially adaptable for use on fuel tanks of automobiles, which will prevent starting of the engine and also obviates the removal of the fuel from the tank.

Another object of this invention is the provision of a tank safety lock of the above 20 stated character, which shall be simple, durable and efficient, and which may be manufactured and sold at a comparatively low cost.

With these and other objects in view as 25 will become more apparent as the description proceeds, the invention consists in certain novel features of construction, combination, and arrangement of parts as will be hereinafter more fully described and 30 claimed.

For a complete understanding of my invention, reference is to be had to the following description and accompanying drawings in which:—

40 Figure 1 is a vertical sectional view, illustrating a gas tank safety lock, constructed in accordance with my invention,

Fig. 2 is a top plan view illustrating the same,

45 Fig. 3 is a detail view illustrating a closure element,

Fig. 4 is a detail view illustrating a removable plug.

Referring in detail to the drawings, the 50 numeral 1 indicates a fuel tank having the usual filling opening 2 and outlet nozzle 3 to which is connected a pipe 4 and which usually leads to the carbureter of the engine (not shown).

55 A closure element 5 consists of a body 6 which has formed thereon an annular por-

tion 7 adapted to fit within the opening 2 and be permanently secured thereto in any desired manner. The body 6 overlies the opening 2 and projects beyond the same and 60 is provided with a screw threaded opening 8 that extends through the annular portion 7 to receive a removable plug 9 which is threaded into said opening 8. The plug 9 is provided with a vent opening 10 to permit the fuel within the tank 1 to be under atmospheric pressure. The plug 9 is provided with a screw threaded opening 11 extending therethrough which receives a 65 valve stem 12 that has its upper portion 70 screw threaded for co-operation with the screw threads in the opening 11 and has threaded to its lower end a valve 14 of the needle type adapted to engage a valve seat 15 formed in the outlet nozzle 3.

A locking arm 16 is pivoted to the upper end of the valve stem 12 as illustrated at 75 17 and normally lies in slots 18 and 19 formed in the plug 9 and closure elements 5. The body 6 of the closure elements has formed 80 thereon spaced ears 20 to receive the free end of the locking arm 16 and are provided with alining openings 21 to receive a padlock or like locking means to prevent the arm 16 from being swung out from between 85 said ears. When the arm 16 is between the ears, and in the slots 18 and 19 the valve 14 is in engagement with the valve seat 15 preventing the fuel in the tank from passing 90 into the pipe 4 and also locking or holding 95 the plug 9 against being removed from the closure element 5. When it is desired to fill the tank 1 with fuel, the arm 16 is released between the ears 20 and swung vertically and the valve stem is turned in relation to 100 the plug 9 to release the tension of the valve 14 on the seat 15 and the plug 9 is then unthreaded from the opening 8 in the body 6 of the closure element 5, whence fuel can 105 then be readily poured into the tank.

To permit fuel to pass into the pipe 4 from the tank 1, the arm 16 is released from between the ears and swung vertically and by rotating the stem 12, the same is elevated disengaging the valve 14 from the seat 15 permitting the fuel to flow through the nozzle 3 into the pipe 4.

While I have shown and described the preferred embodiment of my invention, it will be understood that minor changes in 110 construction, combination, and arrangement of parts may be made without departing

from the spirit and scope of the invention as claimed.

Having thus described my invention, what I claim is:

- 5 A device of the character set forth including a tank having a filling opening and a nozzle provided with a valve seat, a closure element permanently secured in said opening, a plug threaded in said closure element and having a groove and a screw threaded opening in communication with said groove, a valve stem threaded in said opening, a valve secured to said stem and
- 10

engaging the seat, apertured ears formed on the closure element, an arm pivoted to the valve stem and lying within the groove and between the ears, and a fastening means adapted to extend through the apertured ears.

In testimony whereof I affix my signature 20 in presence of two witnesses.

ALBERT B. BURRESE.

Witnesses:

ONEY POWELL,
J. B. HATCHETT.
